tion of Michigan

Application June 23, 1948, Serial No. 34,772

21 Claims. (Cl. 254—126)

1

This invention relates to hoisting apparatus and is an improvement in hoisting apparatus of the character shown in my patent application Serial No. 15,827, filed March 19, 1948, and Patents Nos. 2,576,907, 2,576,908, and 2,576,158, issued November 27, 1951.

More specifically the invention relates to improvements in hoisting apparatus which is particularly adapted for hoisting vehicles.

In my above applications there are disclosed various embodiments of hoisting apparatus in which are included a boom member that is shiftable between substantially horizontal and substantially vertical positions by various actuating mechanisms each of which includes a system of levers which, in the horizontal position of the boom member, is more or less nested with the boom member in order that the boom member and lever assembly be accommodated within a space of limited height when the boom member is in its lower position. The lever systems of these hoisting apparatuses have upper ends pivoted directly to the boom member at locations intermediate their lengths, as in my Patents Nos. 2,576,907 and 2,576,158, or pivoted to fixed extensions similarly located on the boom members, as in my Patent No. 2,576,908 and application Serial No. 15,827. In all cases the boom members are raised and lowered by producing relative approaching and separatory movements respectively of the lower ends of the boom members.

One of the characteristics of a lever system and boom member assembly of this kind is that during initial raising of the boom member from its lowermost position, many times as much force is required than that which is required to produce the final increments of upward movement of the boom member to its substantially vertical position. This is because the angle between the boom member and the effective lever arm of the system of levers by which it is raised is not much less than 180° when the boom member is in its lowermost position and decreases gradually as the boom member is raised. As the angle between this effective lever arm and the boom member decreases the mechanical advantage of the entire system increases. Thus the maximum force required during the starting phases of elevating a load determines the size and capacity of the power driving mechanism involved.

Some reduction in the force required to produce initial lifting of a load by hoisting apparatus of this character can be made, as illustrated in my Patent No. 2,576,908 and applica-

2

tion Serial No. 15,827, by fixing extensions on the boom member which project upwardly from it when it is in its lower position and then pivotally attaching the boom lifting levers to the upper ends of such extensions. This reduction in the initial force requirement can be only limited, however, because excessive upward projection of such extensions must be avoided in order to accommodate the hoisting apparatus in a space of limited height and to allow clearance for accommodating driving of a vehicle over the hoisting apparatus to a position from which it may be lifted by it.

One of the main objects of this invention is 15 to provide a system of levers in hoisting apparatus of this character which materially decreases the force required to initially lift a load and which is entirely accommodatable in a space having no greater height than that required for the boom member when the latter is 20 in its substantially horizontal position.

Another object of the invention is to provide 25 in hoisting apparatus, a system of levers of this kind which accomplishes the above results while confining the upward and downward movements of a load on the apparatus to a course which does not depart significantly from a vertical path.

Another object of the invention is to provide 30 a system of levers for raising and lowering the boom member of hoisting apparatus of this kind which may be nested in substantially parallelism with the boom member when the latter is in its horizontal position and shifted without elevating the boom member to a position relative 35 to the boom member at which it has a more favorable mechanical advantage during initial boom raising operation.

A further object of the invention is to provide 40 a system of levers of this kind which can be contracted into unobstructing relationship with respect to a vehicle being driven into position to be lifted.

A still further object of the invention is to 45 provide a boom member controlling lever system of this kind which rigidifies the boom member.

Other objects of the invention are to provide 50 a combination of link and lever elements in a boom member controlling lever system of this kind which are adapted to be substantially aligned when the boom member is in its horizontal position, to provide resilient means which is energizable during lowering of the boom member for shifting the link and lever elements out

of substantial alignment preparatory to initial raising of the boom member; to provide an abutment on the boom member which is engageable with the link element for holding the link against movement in one direction with respect thereto beyond a predetermined initial boom raising position; to provide an abutment on the lever element which is engageable with the link element when the boom member is in its substantially vertical position for limiting relative movement between the link and lever elements and rigidifying the lever system by tensioning all pivotal connections embodied therein.

Another object of the invention is to provide in screw type actuating mechanisms having an irreversible pitch for positively selectively raising and lowering the boom members of a multiple unit hoisting apparatus, an improved releasable nut member and control means therefor by which the screw element of the mechanism may be releasably coupled with a boom member for operating it.

Another object of the invention is to provide improved means for releasably fixing one hoisting unit of hoisting apparatus of this kind in a plurality of different positions with respect to another hoisting unit thereof in order to accommodate lifting of vehicles of diverse lengths and constructions.

An illustrative embodiment of the invention is shown in the accompanying drawings, in which:

Figure 1 is a perspective view showing hoisting apparatus, embodying the invention, in its elevated position.

Figure 2 is a fragmentary side elevational view showing one of the hoisting units of the apparatus of Figure 1, in its fully contracted lowermost position.

Figure 3 is a fragmentary side elevational view, similar to Figure 2, but showing the lever system of the hoisting unit shifted from its fully contracted position of Figure 1, to a more favorable mechanical advantage position preparatory to a hoisting operation.

Figure 4 is a fragmentary side elevational view showing in full lines one of the hoisting units illustrated in Figure 1, in its upper position and showing an intermediate position of said unit in dot and dash lines.

Figure 5 is a plan view of the hoisting unit illustrated at the right of Figure 1.

Figure 6 is a fragmentary longitudinal vertical sectional view taken on the line 6—6 of Figure 5.

Figure 7 is a transverse vertical sectional view taken on the line 7—7 of Figure 5.

Figure 8 is a vertical sectional view taken on line 8—8 of Figure 1.

Figure 9 is a transverse vertical sectional view taken on the line 9—9 of Figure 3.

Figure 10 is a transverse vertical sectional view taken on line 10—10 of Figure 5.

In Figure 1 of the drawings is illustrated hoisting apparatus embodying the invention which comprises hoisting units A and B each of which are substantially identical, the description of one of which will serve, in all but certain respects hereinafter specified, for the others. These hoisting units are particularly constructed to lift vehicles but may be readily adapted to the lifting of numerous other articles. They are preferably operatively mounted on a track comprising spaced rails 10 and 11 of channel-shaped cross section having inwardly facing upper flanges 12 and 13 and lower flanges 14 and 15. The rails 10 and 11 may be mounted in a shallow groove formed in

a platform structure (not shown) which may be disposed upon a floor structure or they may be mounted in a shallow groove (not shown) of a floor structure with the upper flanges 12 and 13 flush with the floor surface.

The hoisting units A and B each include a shiftable carriage, generally designated by the numeral 17, having a horizontal base plate 18 and a vertically upstanding flange 19. Provided on each of the opposite ends of the shiftable carriage are wheels 20 and 21 which are received between the flanges 12 and 14 and 13 and 15 of the rails 10 and 11, respectively. The wheels 20 and 21 are journaled on the outer end portions of trunnions 22 and 23, which are respectively mounted on and extend outwardly from end flanges 24 and 25 of the carriage 17. The end flanges 24 and 25 may be welded to or formed integral with the base plate 18 and flange 19 of the carriage 17.

Each hoisting unit includes a boom member, generally designated by the numeral 29, which comprises a pair of channel members 30 and 31 having outwardly facing web portions and provided with solid lower end portions 30' and 31', respectively. The solid lower end 30' of the channel member 30 is apertured and journaled on the trunnion 22 at a location between the wheel 20 and end flange 24, as shown in Figure 7. The solid lower end 31' of the channel member 31 is apertured and journaled on the trunnion 23 at a location between the wheel 21 and the end flange 25.

A load receiving seat, generally designated by the numeral 36, is pivotally mounted on the upper ends of the channel members 30 and 31, as illustrated in Figures 1 and 4. The load receiving seat 36 comprises a bar 37 having upwardly extending notched flanges 38 provided on its opposite extremities for receiving a vehicle axle or other portion of a load to be lifted. Provided on the opposite side of the bar 37 are spaced downwardly extending ears 39 for receiving pins 40 by which the seat 36 is pivotally mounted on the upper ends of the channel members 30 and 31.

When the boom member comprising the channel members 30 and 31 is in its upper most position, the lower side of the bar 37 seats upon the upper extremities of the channel members. During movement of the boom member 29 from its lower to its upper position the seat 36 is retained in a substantially horizontal position by parallelogram mechanism including link members 41 extending substantially parallel to the channel members 30 and 31 which are pivotally attached at their upper ends by a pin 42 to rigid arms 43 extending from the lower side of the bar 37 of the seat member, as shown in Figure 4. The lower ends of the links 41 are pivotally attached by pins 44 carried by ears 44' extending upwardly from the base portion 18 of the carriage 17. The pivotal axes provided by the pins 42 and 44 are equidistant from the pivotal axis of the seat 36 provided by the pins 40 and the pivotal axis of the boom member provided by the trunnions 22 and 23, respectively. This provides a parallelogram mechanism which retains and supports the seat 36 in horizontal load supporting position during movement of the boom member 29 between its lower and upper positions. When the boom member is in its upright position the seat 36 is supported in horizontal position by engagement of its lower side with the upper extremities of the channel members 30 and 31.

The boom member 29 is supported and guided

during its movements by a lever system, generally designated by the numeral 45, which includes a rigid yoke element comprising an intermediate span part 46 and spaced rigidly connected link arms 47. The span part 46 and link arms 47 may be integrally formed, welded or otherwise suitably rigidly connected. The free ends of the link arms 47 are journalled on trunnions 48 fixed to and extending inwardly from the bars 30 and 31 of the boom member 29 at aligned locations intermediate the length of the bars 30 and 31. Provided on the span part 46 of the yoke are spaced bearings 49 on which are journalled the upper end portions of a pair of levers 50. As shown in Figures 1 to 5, the levers 50 are straight throughout the major portions of their length but are provided with slightly upwardly curved upper end portions. The lower ends of the levers 50 are pivotally attached to a cross bar 51 which extends between the rails 10 and 11 of the track structure. This cross bar is provided with upwardly extending shoes 52, one of which is engaged between the flanges 12 and 14 of the rail 10 and the other of which is engaged between the flanges 13 and 15 of the rail 11. The cross bar 51 includes integral upwardly extending pairs of flanges 53 and 54 and a central bearing portion 55 having a bore 56. The lower end of one lever 50 is received between the flanges 53 and pivotally attached thereto by a pin 57 and the lower end of the other lever 50 is received between the flanges 54 and pivotally attached thereto by a pin 58. The cross bar 51 is preferably releasably fixed to the side rails 10 and 11 by pins 59 or other suitable means such as bolts, capscrews and the like. The bars 30 and 31 of the boom 29 are adapted to be received between the shoes 52 and the adjacent flanges 53 and 54 respectively when the hoist is in its lower position.

The hoisting unit B is substantially identical to the hoisting member A and similar parts are designated by the same numeral. However, the unit B has a slightly different seat generally designated by the numeral 36' which includes a bar 37' having a channel in its upper side bounded by flanges 60 in which rests 61 are shiftably mounted. Each rest 61 has a notch 62 in its upper side for receiving a portion of the load to be lifted. The lower ends of the levers 50 of the hoisting unit B are pivotally attached to a cross bar 51' which is substantially identical to the cross bar 51 of unit A. Provided on the cross bar 51' are pairs of upstanding flanges 63 and 64. The lower end of one lever 50 is received between the flanges 63 and pivotally attached thereto by a pin 65 and the lower end of the other lever 50 is received between the flanges 64 and pivotally attached thereto by a pin 66. The cross bar 51' has an upstanding flange 67 extending along its right side, as viewed in Figure 5, on the right side surface of which is vertically shiftably mounted a yoke-shaped locking member 68. The locking member 68 has downwardly extending leg portions 69 slidably received in brackets 70. The lower end portions of the legs 69 are adapted to be selectively positioned in aligned pairs of slots 71 formed in plates 72 which are rigidly fixed to the rails 10 and 11 or other suitable stationary supporting structure adjacent thereto. By raising the yoke-shaped locking member 68 the ends of the legs 69 may be disengaged from one pair of aligned slots 71 and the cross bar may be moved relative to the rails and secured against displacement from its new position by merely lowering the locking member 68. In this way the

hoisting apparatus may be conditioned for lifting loads or vehicles of different lengths or constructions.

The driving apparatus by which the boom members 29 of the hoisting units A and B may be selectively individually and simultaneously positively raised and lowered comprises a screw member, generally designated by the numeral 73, having threads 74 thereon associated with each of the boom members 29, respectively. The screw member 73 preferably comprises a plurality of sections which are connected together in longitudinal alignment by couplings 75. The respectively opposite end portions of the screw member 73 are journalled in bearings provided in transverse cross members 76 and 77 which extend between and are fixed to the ends of the rails 10 and 11. One or more intermediate cross member 78 also extends between and is fixed to intermediate portions of the rails and is provided with bearings for rotatively supporting the screw member at locations between its ends. The bearing 56 of the cross bar 48 also rotatively supports an intermediate portion of the screw member.

Each carriage 17 of the boom members A and B includes a releasable nut member, generally designated by the numeral 79, which is adapted to be threadably engaged with the screw 73 in the manner hereinafter set forth. The nut member 79 comprises separable internally threaded, semi-cylindrical nut sections 80 which are provided with oppositely extending stems 81. Each stem 81 is slidably mounted in a bearing block 82 for movement transversely of the axis of the screw 73, as shown in Figure 7. The nut sections 80 may be simultaneously moved inwardly and outwardly relative to each other in order to engage and disengage the threads of the nut section and screw, respectively. This movement is produced by an eccentric 83 which is rotatably mounted in an aperture 84 formed in each stem 81 respectively. Each eccentric 83 is non-rotatably fixed on a square section of a shaft 85 which is journalled in spaced bearing blocks 86 for rotation about an axis substantially parallel to the axis of the screw 73. Provided on each shaft 85 is a sprocket 87. The sprockets 87 are connected together for simultaneous rotation by an endless chain 88. A handle 89 is fixed on one of the shafts 85 for rotating both eccentrics 83 which as illustrated in Figure 7 have opposite eccentricity in order to oppositely shift the nut sections 80 during rotation of the sprockets 87 in the same direction. When the nut sections 80 are disengaged from the screw 73 the screw is permitted to turn while the carriage 17 remains at rest. When the nut sections are engaged with the threads of the screw, rotation of the screw in opposite directions shifts the carriage 17 and lower end of the boom member 29 which is pivotally attached to it, longitudinally of the rails in correspondingly opposite directions. It should be noted, that, as shown in Figures 1 and 7, the carriage 17 has a side wall 90 on the external side of which are located the sprockets 87 and chain 88. The end portions of the side wall 90 of the carriage 17 serve as abutments to limit the upward movement of the boom member to a substantially vertical position. Each boom member may thus be selectively coupled with and uncoupled from the drive screw 73.

The cooperating threads of the screw member 73 and nut sections 80 have an irreversible pitch and therefore, while rotation of the screw positively drives the boom member 29 upwardly and

downwardly, the weight of an elevated load supported on the boom member cannot rotate the screw member 73. Accordingly, the threaded engagement between the screw member 73 and the nut sections 80 serves as a lock to positively hold each boom member 29 in any selected position to which it is shifted by rotation of the screw member.

The screw member 73 is preferably driven thru suitable reduction gear mechanism 91, which is in turn driven by a reversible electric motor 92. The details of the gear mechanism are fully disclosed in my pending application Serial No. 15,827. Any gear reduction mechanism may be used for this purpose.

The electric motor 92 may be provided with any suitable control circuit by which the motor 92 may be selectively driven in opposite directions, started and stopped under control of a portable switch 92', such for example as the control circuit shown in my above pending patent application. This circuit may, if desired, include suitable limit switches for interrupting the motor operation at predetermined upper and lower positions of the boom members 29, as shown in the above patent application.

In operation of the hoisting apparatus in lifting a vehicle, the vehicle is driven over the base structure including the rails 10 and 11 while the hoisting units are fully lowered and substantially completely nested between the rails 10 and 11 with all but the load receiving seats 36 and 36' disposed below the plane of the upper extremities of the rails. The wheels of the vehicle may be supported by the floor in which the base structure is submerged. The vehicle may be brought to rest in such position as to cause the seat 36 of the hoisting unit A to register with and receive the rear axle of a vehicle as the seat is elevated in the manner hereinafter set forth. The position of the vehicle relative to the seat 36 may be predetermined in any manner as for example, by providing a depression in the base structure adjacent the rails 10 and 11, as illustrated in the above patent application. The seat 36' of the hoisting unit B may be so positioned as to move into registration with and receive any suitable structure at the front end of the vehicle by disengaging the threads of the nut sections 80 and screw 73 as heretofore set forth. The cross bar 51' may be released for movement relative to the rails by lifting the lock member 68 to disengage its end portion 69 from the slotted plate 72. With the parts of the hoisting unit B in the above described condition, this hoisting unit may be manually shifted in either direction to properly position its seat 36' where desired. The nut sections 80 may be thereafter reengaged with the screw 73 and the lock member 68 may be returned to locked engagement with the plates 72 at a new position thereby placing the hoisting apparatus in condition for operation.

The hoisting unit may be mechanically shifted after the lock member 68 has been lifted from the plates 72, by allowing the nut sections 80 of hoisting unit B to remain engaged with the screw 73 and disengaging the nut sections 80 of the hoisting unit A from the screw. Rotation of the screw 73 in opposite directions by the motor 92 under these conditions will shift the hoisting unit B in corresponding opposite directions along the base structure while the locking member 68 is released.

The relative positions of each boom and its associated lever system in the fully lowered posi-

tion of the boom is illustrated in Figures 2 and 6 in which is shown spring members 93 one of which is mounted on each side rail 30 and 31 of the boom member. Each spring 93 has a free end portion which is adapted to engage one of the lever arms 47 of the yoke structure shown in Figure 9 when the lever system is moved to its lowermost position shown in Figure 2. Each spring 93 is adapted to be loaded by the last increment of downward movement of the yoke member from the position shown in Figure 3 to the position shown in Figure 2.

When the screw 73 is rotated in a forward direction each boom member is shifted in a substantially horizontal path to move the linkage system from the position shown in Figure 2 to the position shown in Figure 3. This change in the angularity of the lever elements 50 with respect to the boom member is brought about without lifting the load or engaging the seats 36 and 36' with it. Counter-clockwise rotation of the link arms 47 from the position shown in Figure 2 to the position shown in Figure 3 is initially assisted by the springs 93 which serve to guard against locking of the lever elements 50 and link arms 47 in an aligned relationship. The left end portions of the lever elements 50 are slightly curved upwardly with respect to the main links thereof in order to further guard against aligning of the pivotal axes of the connections between the link arms and lever elements and between the yoke member and the boom member. This counter-clockwise rotation of the link arms 47 is arrested when the link arms are substantially normal to the length of the boom member by engagement with stops 94 one of which is secured to each of the bars 30 and 31 of the boom member 29. When the lever elements 50 are angularly disposed with respect to the boom member, as shown in Figure 3, they are in position to exert a favorable mechanical advantage in initially elevating the load engaging seat of the hoisting unit into contact with the load during movement of the left end of the boom unit toward the fixed cross bar 51 by further forward rotation of the screws 73. By the time the seat 36 of the boom member engages the load the mechanical advantage of the lever system has been further increased. Therefore the force required to be applied by the screw 73 during initial lifting of the load is reduced by this system of levers and accordingly the capacity requirement of the motor 92 is reduced. As the boom member reaches its intermediate position shown in dot and dash lines in Figure 4 the link arms 47 swing into substantially aligned overlapping relationship with respect to the lever elements 50 and at this position each link arm engages a stop 95 provided on each of the lever elements 50 for limiting relative rotation of the link arms 47 and lever elements 50 beyond this relationship. Further movement of the lower end of the boom member toward the lower fixed ends of the lever elements 50 elevates the boom member to the full line position shown in Figure 4 while the link arms remain in substantially aligned overlapping relation to the lever elements. The need for an increased mechanical advantage in the lever system of a hoisting unit of this kind is illustrated in Figure 4 wherein it will be seen that approximately the last quarter of the upward movement of the seat 36 is produced during approximately the last half of the travel of the lower end of the boom member toward the lower ends of the lever elements 50, whereas the first half of the travel of the lower

end of the boom member in its horizontal path produces approximately three fourths of the upward vertical movement of the seat 36. This results from the decrease in the angle between the boom member 29 and link element 50 from approximately 180° at the lower position of the boom member to a minimum angle at its upper position.

Lowering of the load is accompanied by a reverse operation of the screw 13 and during this lowering operation the link arms 47 undergo reverse action until they reach the position shown in Figure 3 at which time the seat 36 has been moved out of contact with the load. Further reverse drive of the screw 13 shifts the boom member horizontally and brings the link arms 47 and lever elements 50 into the position shown in Figure 2 wherein they do not extend above the horizontal plane of the upper extremities of the rails 10 and 11.

The engagement of the stops 95 with the link arms 47 tensions and rigidifies the linkage in such a way as to compensate for any wear or looseness in the pivots. The rigidly connected link arms 47 and span part 46 of the yoke structure of the link system rigidifies the boom member at a location intermediate its ends. A groove 56 may be formed in the span part 46 to receive the screw when the linkage mechanism is in its lowermost nested position. The lower end portion of the boom member may be further rigidified by cross braces 97 which do not in any way interfere with the action of the apparatus.

A favorable mechanical advantage is obtained during initial load raising stages of the operation of the apparatus without requiring the projection of any portions of the linkage system above the rails 10 and 11 when the apparatus is in its lower position. The seats 36 and 36' of the hoisting units are confined during their upward and downward movements to paths which do not depart significantly from a vertical course for any tendency of the load receiving seats to shift horizontally due to the pivotal components of the movements of the boom members is compensated for by the opposite horizontal shifting component which results from movements of the lower ends of the boom members horizontally toward the lower ends of the link elements 50 and 50' of the units A and B, respectively.

Although but one specific embodiment of the invention is herein shown and described, it will be understood that various changes in the details and construction thereof may be made without departing from the spirit and scope of my invention.

I claim:

1. In hoisting apparatus comprising a base structure and a boom member mounted on said base structure for shifting movement between generally vertical and generally horizontal positions and having a load support on one end; mechanism for shifting said boom member between said positions including a lever element, a link element pivoted at one end to an end portion of said lever element and at its opposite end to said boom member at a location intermediate the length of the latter, an abutment on said boom member engageable with said link element for limiting pivotal movement of said link element in one direction relative to said boom member, and means for producing relative shifting movements in respectively opposite directions between the other end of said lever element and the other end of said boom member.

for respectively raising and lowering said boom member through the action of said link and lever elements.

2. In hoisting apparatus comprising a base structure and a boom member mounted on said base structure for shifting movement between generally vertical and generally horizontal positions and having a load support on one end; mechanism for shifting said boom member between said positions including a lever element, a link element pivoted at one end to an end portion of said lever element and at its opposite end to said boom member at a location intermediate the length of the latter, an abutment on said boom member engageable with said link element for limiting pivotal movement of said link element in one direction relative to said boom member, and an abutment on said lever element engageable with said link element for limiting pivotal movement of said link element in one direction relative to said lever element, and means for producing relative shifting movements in respectively opposite directions between the other end of said lever element and the other end of said boom member for respectively raising and lowering said boom member through the action of said link and lever elements.

3. In hoisting apparatus comprising a base structure and a boom member mounted on said base structure for shifting movement between generally vertical and generally horizontal positions and having a load support on one end; mechanism for shifting said boom member between said positions including a lever element, a link element pivoted at one end to an end portion of said lever element and at its opposite end to said boom member at a location intermediate the length of the latter, an abutment engageable by said link element for limiting pivotal movement thereof in one direction relative to said boom member to a position substantially normal to said boom member and means for producing relative shifting movements in respectively opposite directions between the other end of said lever element and the other end of said boom member for respectively raising and lowering said boom member through the action of said link and lever elements.

4. In hoisting apparatus comprising a base structure and a boom member mounted on said base structure for shifting movement between generally vertical and generally horizontal positions and having a load support on one end; mechanism for shifting said boom member between said positions including a lever element, a link element pivoted at one end to an end portion of said lever element and at its opposite end to said boom member at a location intermediate the length of the latter, an abutment engageable by said link element for limiting pivotal movement thereof in one direction relative to said boom member to a position substantially normal to said boom member when the latter is spaced from its vertical position, a second abutment engageable by said link element when said boom member is substantially in its vertical position for limiting pivotal movement of said link element in an opposite direction, and means for producing relative shifting movements in respectively opposite directions between the other end of said lever element and the other end of said boom member for respectively raising and lowering said boom member through the action of said link and lever elements.

5. In hoisting apparatus comprising a base structure and a boom member mounted on said

11

base structure for shifting movement between generally vertical and generally horizontal positions and having a load support on one end; mechanism for shifting said boom member between said positions including a lever element, a link element pivoted at one end to an end portion of said lever element and at its opposite end to said boom member at a location intermediate the length of the latter, means for producing relative shifting movements in respectively opposite directions between the other end of said lever element and the other end of said boom member for respectively raising and lowering said boom member through the action of said link and lever elements, said means being adapted to releasably hold said link and lever elements in approaching alignment with each other and in substantially parallel relation to said boom member when the latter is in its generally horizontal position, and a resilient element energizable during movement of said link and lever elements into said aligned relationship for urging said elements toward angular relationship with respect to each other.

6. In hoisting apparatus comprising a base structure and a boom member mounted on said base structure for shifting movement between generally vertical and generally horizontal positions and having a load support on one end; mechanism for shifting said boom member between said positions including a lever element, a link element pivoted at one end to an end portion of said lever element and at its opposite end to said boom member at a location intermediate the length of the latter, an abutment engageable by said link element for limiting pivotal movement thereof in one direction relative to said boom member to a position substantially normal to said boom member when the latter is spaced from its vertical position, a second abutment engageable by said link element when said boom member is substantially in its vertical position for limiting pivotal movement of said link element in an opposite direction, means for producing relative shifting movements in respectively opposite directions between the other end of said lever element and the other end of said boom member for respectively raising and lowering said boom member through the action of said link and lever elements, said means being adapted to releasably hold said link and lever elements in approaching alignment with each other and in substantially parallel relation to said boom member, and a resilient element energizable during movement of said link and lever into said aligned relationship for urging said elements toward angular relationship with respect to each other.

7. Hoisting apparatus comprising a base structure, a boom member mounted on said base structure for shifting movement between generally horizontal and generally vertical positions, said boom member having a load receiving seat on one end and the other end shiftably connected to said base structure for movement therealong, a link and lever assembly for shifting said boom member between said positions including means pivotally connecting one end of said link to said boom member at a point intermediate the ends thereof and means pivotally connecting the other end of said link to one end of said lever, means for pivotally connecting the other end of said lever to said base structure, said link and lever being adapted to substantially align longitudinally with each other and to be disposed in angular relationship with respect to each other

12

while said boom member is in its generally horizontal position so as to produce a favorable mechanical advantage during initial movement of said boom member from its generally horizontal position, and mechanism for relatively shifting said other end of said lever and the other end of said boom member toward and away from each other for raising and lowering said boom member respectively, said mechanism being adapted to initially shift said boom member and link relative to each other while said boom member is in its generally horizontal position in order to move said link and lever into angular relationship before said boom member is started toward its generally vertical position.

8. Hoisting apparatus comprising spaced rails, a boom member disposed between said rails having a load receiving seat pivotally mounted on one end thereof, means pivotally connecting one end of said boom member with said rails and adapted to hold said end of said boom member against vertical displacement relative to said rails while permitting longitudinal shift of said one end of said boom member along said rails, a link and lever assembly for controlling shifting of said boom member between generally horizontal and generally vertical positions including a link element pivoted at one end to said boom member and a lever element having one end pivotally connected to the other end of said link element, means for fixing the opposite end of said lever element against movement relative to said rails, said link and lever assembly being substantially alignable with each other and receivable between said rails when said boom member is in its horizontal position, and power actuated mechanism comprising a member operatively connected with said first mentioned means for initially shifting said boom member bodily only longitudinally of said rails to bring said link and lever elements into an angular relationship to produce a favorable mechanical advantage for subsequently shifting said one end of said boom member toward the fixed end of said lever element to move said boom member from its horizontal position toward its vertical position.

9. Hoisting apparatus comprising a base structure, a boom member mounted on said base structure for shifting movement between generally horizontal and generally vertical positions comprising laterally spaced bars, a load receiving seat connecting the upper ends of said bars, a carriage on said base structure shiftable longitudinally thereof and pivotally connecting the lower ends of said bars, an inwardly extending trunnion fixed to each of said bars respectively at horizontally aligned locations intermediate their ends, a rigid yoke member comprising arm elements journaled on said trunnions and a connecting span element having spaced bearing portions, a pair of levers each having one end journaled on a bearing portion of said span element respectively and adapted to substantially align with said yoke when said boom member is in a horizontal position, means pivotally connecting the opposite ends of said levers with said base structure, and means for shifting said carriage toward said last mentioned ends of said levers to initially bodily shift said boom member and bring said levers and yoke into angular relationship and to subsequently urge said boom member toward its vertical position under the control of said yoke and levers.

10. Hoisting apparatus comprising a base structure, a boom member mounted on said base

structure for shifting movement between generally horizontal and generally vertical positions comprising laterally spaced bars, a load receiving seat connecting the upper ends of said bars, a carriage on said base structure shiftable longitudinally thereof and pivotally connecting the lower ends of said bars, an inwardly extending trunnion fixed to each of said bars respectively at horizontally aligned locations intermediate their ends, a rigid yoke member comprising arm elements journalled on said trunnions and a connecting span element having spaced bearing portions, a pair of levers each having one end journalled on a bearing portion of said span element respectively and adapted to substantially align with said yoke when said boom member is in a horizontal position, means pivotally connecting the opposite ends of said levers with said base structure, an abutment on said boom member engageable by said yoke member for limiting pivotal movement of the latter in one direction to a predetermined angular relationship with respect to said boom member, an abutment on one of said lever members engageable with said yoke member for limiting pivotal movement of the latter in an opposite direction to a predetermined angular relation to said lever elements and means for shifting said carriage toward said last mentioned ends of said levers to initially bodily shift said boom member and bring said levers and yoke into angular relationship and to subsequently urge said boom member toward its vertical position under the control of said yoke and levers.

11. Hoisting apparatus comprising a base structure, a boom member mounted on said base structure for shifting movement between generally horizontal and generally vertical positions comprising laterally spaced bars, a load receiving seat connecting the upper ends of said bars, a carriage on said base structure shiftable longitudinally thereof and pivotally connecting the lower ends of said bars, an inwardly extending trunnion fixed to each of said bars respectively at horizontally aligned locations intermediate their ends, a rigid yoke member comprising arm elements journalled on said trunnions and a connecting span element having spaced bearing portions, a pair of levers each having one end journalled on a bearing portion of said span element respectively and adapted to substantially align with said yoke when said boom member is in a horizontal position, means pivotally connecting the opposite ends of said levers with said base structure, an abutment on said boom member engageable by said yoke member for limiting pivotal movement of the latter in one direction to a predetermined angular relationship with respect to said boom member, an abutment on one of said lever members engageable with said yoke member for limiting pivotal movement of the latter in an opposite direction to a predetermined angular relation to said lever elements, a nut member on said carriage, and means for shifting said carriage toward and away from said last mentioned ends of said levers for raising and lowering said boom member respectively comprising a power driven screw element in threaded engagement with said nut member, said boom member being initially bodily shiftable horizontally by said screw element for shifting said yoke and levers into angular relationship prior to movement of said boom member from its horizontal position toward its vertical position.

12. Hoisting apparatus comprising a base structure, a boom member mounted on said base

structure for shifting movement between generally horizontal and upper positions, mechanism for shifting said boom member between said positions including an actuating means having an element operatively connected to said boom member and including a toggle acting lever system comprising pivotally connected link and lever elements having adjacent ends pivotally connected together and having their spaced end pivotally connected to said boom member and base structure respectively and adapted to nest in substantially aligned relation substantially between the horizontal bounding plane of said boom member when the latter is in its horizontal position and to be projected from between said planes into angular relation with respect to each other for providing a favorable mechanical advantage during initial raising of said boom member from its horizontal position, and abutment means cooperating between said boom member and lever system for rigidifying said boom member in its upright position.

13. Hoisting apparatus comprising a base structure, a boom member mounted on said base structure for shifting movement between generally horizontal and upper positions, mechanism for shifting said boom member between said positions including an actuating means having an element operatively connected to said boom member and including a toggle acting lever system, means pivotally connecting one end of said toggle acting lever system to said boom member and the opposite end thereof to said base structure and abutment means cooperating between said boom member and lever system to limit the action of said lever system in one direction when said boom member is in its upper position.

14. Hoisting apparatus comprising a base structure, a boom member mounted on said base structure for shifting movement between generally horizontal and upper positions, mechanism for shifting said boom member between said positions including an actuating means having an element operatively connected to said boom member and including a toggle acting lever system pivotally attached to said boom member and base structure and comprising pivotally connected link and lever elements, and abutment means coacting with said lever system to limit the action of said lever system in one direction under the influence of said actuating element and adapted to cooperate with said actuating element in tensionally rigidifying said pivotal connections when said boom member is in its upper position.

15. Hoisting apparatus comprising a base structure, a boom member, means mounting said boom member on said base structure for shifting movement between generally horizontal and upper positions, a screw element rotatably mounted on said base structure, mechanism for releasably coupling said boom member to said screw element including shiftable nut elements adapted for threaded engagement with said screw element, and manually operable means for simultaneously shifting said nut elements toward and away from each other to engage them with and disengage them from said screw respectively, said manually operable means comprising a rotatable eccentric journalled in each of said nut elements and apparatus for driving said eccentric in respectively opposite directions including a sprocket on each eccentric and a common sprocket chain engaged on said sprockets.

16. Hoisting apparatus comprising a base

structure and a boom member including laterally spaced bars mounted on said base structure for shifting movement between generally vertical and generally horizontal positions and having a load receiving seat mounted on one end and means connecting the other end to said base structure for shiftable movement therealong; mechanism for shifting said boom member between said positions including a pair of lever elements, a pair of link elements, each link element being pivoted at one end to one end of one of said lever elements respectively and pivotally connected at its opposite end to one of said bars respectively at a location intermediate the length of the latter, and means for producing relative shifting movement between the other ends of said lever elements and the other end of said boom member for raising said boom member through the action of said link and lever elements.

17. Hoisting apparatus comprising a base structure and a boom member including laterally spaced bars mounted on said base structure for shifting movement between generally vertical and generally horizontal positions and having a load receiving seat mounted on one end and means connecting the other end to said base structure for shiftable movement therealong; mechanism for shifting said boom member between said positions including a pair of lever elements, a pair of link elements, each link element being pivoted at one end to one end of one of said lever elements respectively and pivotally connected at its opposite end to one of said bars respectively at a location intermediate the length of the latter, a bar extending transversely of said link and lever mechanism interconnecting the adjacent pivoted ends of said link and lever elements, and means for producing relative shifting movement between the other ends of said lever elements and the other end of said boom member for raising said boom member through the action of said link and lever elements.

18. In hoisting apparatus comprising a base structure and a boom member mounted on said base structure for shifting movement between generally vertical and generally horizontal positions and having a load receiving seat mounted on one end and means connecting the other end to said base structure for shiftable movement therealong; mechanism for shifting said boom member between said positions including a lever element, a link element pivoted at one end to one end of said lever element and at its opposite end to said boom member at a location intermediate the length of the latter, and means for producing relative shifting movement between the other end of said lever element and the other end of said boom member for raising said boom member through the relative movement of said link and lever elements.

19. Hoisting apparatus comprising a base structure, a rigid fixed length boom member mounted on said base structure for shifting movement between generally horizontal and generally vertical positions, said boom member having a load support on one end and the other end slidably connected to said base structure for movement therealong, and interconnected link and lever assembly connected between the base structure and an intermediate portion of the boom member for shifting said boom member between said positions including means pivotally connecting one end of said link to said boom member and means pivotally connecting the other end of said link to one end of said lever, means piv-

otally connecting the other end of said lever to said base structure, said link and lever being adapted to substantially align longitudinally with each other and to be disposed in angular relationship with respect to each other while said boom member is in its generally horizontal position, means for producing relative shifting movements in respectively opposite directions between said other end of said lever and the other end of said boom member while the latter is in its horizontal position for respectively contracting said assembly vertically and bringing the link and lever into angular position to produce a favorable mechanical advantage during initial movement of said boom member from its generally horizontal position.

20. In hoisting apparatus comprising a base structure and a rigid fixed length boom member mounted on said base structure for shifting movement relative thereto between generally vertical and generally horizontal positions, said boom member having a load receiving seat pivoted on its upper end and having its lower end shiftably connected to said base structure for movement therealong; mechanism for shifting said boom member between said positions including a lever element pivotally connected at one of its ends to said base structure and shiftably bodily relative to said boom member, a link element pivoted at one end to the other end of said lever element and having a fixed pivotal connection at its opposite end to said boom member at a location intermediate the length of the latter, and means for producing relative shifting movements in respectively opposite directions between said one end of said lever element and the lower end of said boom member for respectively raising and lowering said boom member through the action of said link and lever elements.

21. Hoisting apparatus comprising a base structure, a boom member mounted on said base structure for shifting movement between generally horizontal and upper positions, a load receiving seat on one end of said boom member, means bodily shiftably mounting the other end of said boom member on said base structure, and mechanism for shifting said boom member between said positions including an actuating means having an element operatively connected to said boom member and including a toggle acting lever system comprising link and lever elements pivotally connected together at their adjacent ends and having their spaced ends pivotally connected to said boom member and base structure respectively and adapted to nest in substantially aligned relation substantially between the horizontal bounding plane of said boom member when the latter is in its horizontal position and to be projected from between said planes into angular relation with respect to each other while said boom member is still in its horizontal position for providing a favorable mechanical advantage during initial raising of said boom member from its horizontal position.
